UNITED STATES PATENT OFFICE.

WM. PHELPS AND W. H. HANFORD, OF SYCAMORE, ILLINOIS.

HORSE-POWER MACHINE.

Specification of Letters Patent No. 26,203, dated November 22, 1859.

To all whom it may concern:

Be it known that we, WM. PHELPS and W. H. HANFORD, both of Sycamore, in the county of Dekalb and State of Illinois, have 5 invented a new and Improved Mode of Transmitting Motion to Machinery; and we do hereby declare that the following is a full, clear, and exact description of the construction and operation of this machine, reference being had to the annexed drawings, 10 making a part of this specification.

Figure 1 represents an upright view of the machine, which for convenience we divide into three parts constituting principles 15 of motion and for further convenience of specification are drafted in seven sections, of which—

Fig. 2 represents a section forming the base; A the foundation; B a circular track; 20 e center box.

Fig. 3, a section representing the under surface of the bull wheel E; F, F, F, horizontal shafts; C, C, C, and D, D, D, pairs of upright triplet friction rollers; G, G, G, 25 levers; aa aa aa three pairs of anti-friction rollers. This section in connection with the track B and horizontal drive wheel H forms the first division constituting the first principle of motion.

Fig. 4, a section representing the horizontal drive wheel H.

Fig. 5, a section representing the triplet arms M, M, M; L L L horizontal shafts; I, I, I, and J, J, J, pairs of triplet friction 35 rollers; K, K, K, pulleys. This section in connection with the horizontal drive wheel H, and the horizontal drive wheel O forms the second division, constituting the second principle of motion.

Fig. 6 represents a horizontal drive wheel of which there are two, N and O.

Fig. 7, a section representing the under surface of the triplet beams Q, Q, Q; R, R, R, triplet rollers and shafts. This section 45 in connection with the horizontal drive wheels N and O forms the third division constituting the third principle of motion. P, P, P, posts; Y platform; U represents a small appended section.

Fig. 8, represents the perpendicular main shaft S.

The nature of this invention consists of a horizontal track B, forming a perfect circle, made of iron, or any other material sufficiently hard as to prevent indentation by 55 the rollers resting, or rolling upon it. This

track rests upon a solid foundation A, which may be so constructed as to be portable or permanent. The track to present on its upper surface an oval, true and smooth finish; a characteristic which is to specify all of the friction track-surfaces in this machine. On this track are placed the pairs of triplet-friction rollers C, C, C, and D, D, D, resting on the rolling surface of the first 60 three. These rollers may be constructed wholly or in part of iron, made square on their rolling surfaces where they roll in connection with the track B and horizontal drive wheel H. The largest of these pairs 65 of rollers may be concave on their inner surfaces, corresponding with the rim of the track B. The outer surface may be made convexing, corresponding with their inner surfaces, and they all may be varied in the 70 dimensions of their diameters either for the purpose of increasing or diminishing motion, always preserving equality in their diameters. They are placed at equal distances from each other on the track, and kept in 75 their relative positions by means of the horizontal shafts F, F, F, to which they are made fast at one end, the other pointing toward the center of the foundation, near which, and by means of journals and boxes 80 are connected to the under surface of the bull wheel E, at c, c, c. Toward the other 85 end of the shafts and near to their attachment to the rollers C, C, C, are journals on which rest the pairs of anti-friction rollers aa, aa, aa, which roll in slots on small shafts at or near the verge of the bull wheel E. The bull wheel may be made wholly or in part of iron according to the strength required.

G, G, G, represent levers to which may be attached horses. These pass through loops made fast to the bull wheel.

Fig. 8 represents the perpendicular main shaft S, which passes through the center of 100 the bull wheel and to which it is made fast, except in cases where it is desirous to run the second and third divisions or principles of motion below the foundation and track A and B. Then the main-shaft is made fast 105 at one end to the horizontal drive wheel H passing through, and playing loosely in the center box of the foundation A and bull wheel E, descending to any distance required where near to its lower end may be 110 connected another horizontal drive wheel of sufficient strength to support the weight of

the second and third divisions or principles of motion which may be placed upon it.

The horizontal wheel H may be made wholly or in part of iron, with a center 5 through which passes the main shaft, playing loosely, a characteristic which will specify all of the centers through which it passes excepting in those mentioned above. The rim of this wheel rests upon the summits of the triplet friction rollers D, D, D, and becomes the foundation or rotary track upon which is built the second division constituting the second principle of motion. This division is constructed proportionally 15 after the same manner of the first division, and is placed upon the track or horizontal wheel H resting on the under rolling surfaces of the triplet friction rollers I, I, I. These rollers are attached to the larger rollers 20 J, J, J and all made fast to the horizontal shafts L, L, L, which pass through them connecting at one end by means of boxes and journals to the under surface of triplet arms M, M, M, but at the other end, and outside 25 of the rollers are represented pulleys to which by belts may be connected machinery. Near to one of the pairs of rollers on the outside is a journal which plays in a slot formed in a stud, represented at g Fig. 1. This stud 30 together with five others similar are suspended from and fastened to the triplet beams Q, Q, Q.

On the upper rolling surfaces of the triplet friction rollers J, J, J rests the horizontal drive wheel O, which is constructed 35 in the same manner as the horizontal drive wheel H but some larger in diameter. This wheel becomes the track and foundation of the third division, which is a repetition of 40 the second with the exception that the shafts connecting with the triplet friction rollers R, R, R, point outward to which machinery may be attached either by pulleys and belts, or by tumbling rods as the nature of the case 45 may require. These shafts by means of their journals play in their boxes which are formed in the studs g, g, g, g, g. Between

the horizontal wheel N and the triplet beams Q, Q, Q, is a small appended section U, Fig. 1 in which is represented an arrangement of triplet friction rollers, a repetition of the same principle set forth in the other divisions of the machine. This small section represents a plan whereby gravitating power may be added to the machine by 55 means of the lever above the triplet beams Q, Q, Q, without materially increasing friction to retard the power of the machinery.

Operation of the machine: The action of the pairs of triplet friction rollers C C C 60 and D D D all rolling and rotating in the same direction on the track B, carrying along upon the summits of the rollers D, D, D, the rim of the drive wheel H with increased velocity which becomes a rotary 65 track reversing the motion and driving the pairs of stationary triplet friction rollers I I I and J, J, J, the latter of which rolling in connection with the under surface of the rim of the drive wheel O carrying it along 70 by their friction surface. This horizontal wheel becoming a rotary track as in the case of the horizontal wheel H only the motion is the reverse driving the stationary triplet friction rollers R R R which reverses the 75 motion of the horizontal wheel N, which rotates upon their upper surfaces.

We do not claim as new the producing of a rotary motion in motive powers by the friction of smooth rolling surfaces; but 80

What we claim is,

The combination and arrangement of the wheels and rollers C C C and D D D on track B, and wheel H and frictions rollers i i i and j j j on track H, and friction 85 rollers R, R, R, on rotary track O with rotary drive wheel N and friction rollers U constructed and operated substantially as described.

WILLIAM PHELPS.
W. H. HANFORD.
